UNITED STATES PATENT OFFICE.

EDMUND J. PHELPS, OF MINNEAPOLIS, MINNESOTA.

DESIGN FOR A BICYCLE-FRAME.

SPECIFICATION forming part of Design No. 28,082, dated December 21, 1897.

Application filed May 22, 1897. Serial No. 637,789. Term of patent 7 years.

To all whom it may concern:

Be it known that I, EDMUND J. PHELPS, residing at Minneapolis, in the county of Hennepin and State of Minnesota, have invented and produced a new and original Design for Bicycle-Frames, of which the following is a specification, reference being had to the accompanying drawings, forming part thereof.

In the drawings, Figure 1 is a side elevation of a bicycle-frame embodying my invention. Fig. 2 is a perspective view of the same.

As shown in the drawings, the leading or material features of my design consist in the form or configuration of the single straight mast or standard and the two curved drop-bars connected thereto.

The mast or standard 8 is a straight inclined bar from top to bottom. The upper drop-bar 6 diverges on a curved line from the lower part of the single mast 8 at a point above its lower end and after curving downwardly and then upwardly to the point 7 extends in a straight line to the head 3. The

rear fork 5 extends in a straight line backward from the lower line of the single mast 8. The lower drop-bar 2 extends from the lower end of the mast 8 on the opposite side from the fork 5 and substantially in line with said fork and then curves upwardly in the same plane with the upper drop-bar 6 to the point 4, and then it extends in a straight line to the lower end of the head 3. The two curved drop-bars are connected by the cross-bars 10 and 11.

Having described my invention, what I claim as new, and desire to secure by Letters Patent, is—

The design for a bicycle-frame, as herein shown and described.

In testimony whereof I have hereunto set my hand this 1st day of May, A. D. 1897.

EDMUND J. PHELPS.

In presence of—

C. G. HAWLEY,
RICHARD PAUL.
